UNITED STATES PATENT OFFICE.

JOHN H. SHAW, OF NEW HAVEN, CONNECTICUT.

MOLD FOR CASTING METALS.

No. 853,824.

Specification of Letters Patent.

Patented May 14, 1907.

Application filed May 18, 1906. Serial No. 317,610.

To all whom it may concern:

Be it known that I, JOHN H. SHAW, of the city and county of New Haven and State of Connecticut, have invented new and useful 5 Improvements in Molds for Casting Metals, of which the following is a full, clear, and exact description, when taken in connection with the accompanying drawings, which form a part thereof, and in which—

10 Figure 1 represents a front elevation of a mold embodying my invention, Fig. 2, a top view of the same, Fig. 3, a transverse vertical section on line 3—3 of Fig. 1, Fig. 4, a longitudinal vertical section on line 4—4 of Fig. 3, and Fig. 5, a detail view of a modified 15 form of the locking mechanism for one of the side plates.

In all figures, similar letters of reference represent like parts.

20 This invention relates to molds for casting metals, and particularly to that class of molds made from metal.

When closed metal molds are used, a difficulty exists in that the expansion of the casting in the mold is apt to crack the mold. 25 Various methods have been employed to overcome this difficulty, and the present invention has for its object the production of a novel means for permitting the casting to expand without injury to the mold. To this 30 end, the several parts of the mold are yieldingly held in position so that they are capable of a slight movement upon the expansion of the casting while they are still held in position.

35 To this end, the invention consists of the several improvements and combinations of parts set forth and claimed hereinafter.

Referring to the drawings for a more 40 particular description, the part designated by the letter A represents a plate forming the base or bottom plate of the mold, and B an upright plate rigidly secured thereto forming the back plate of the mold.

45 To the top of the back plate is fulcrumed by a pin C, or other means, a pivoted member D, which when in proper position forms the front of the mold. The member D is provided with a flange E adapted to fit on the 50 bottom plate A of the mold.

F designates a handle secured to the member D to swing it to and from its closed position. The member D is held in its closed position by a hook G fulcrumed at H, and provided with a handle I. The hook G takes 55 into a link J pivoted to a projection K on the

bottom plate A (Figs. 1 and 3). A spring L bears against the under side of the hook G and against the flange E of the member D to hold the hook in position, while allowing the member D a slight play.

M designates the side plates of the mold, which are adapted, as shown more particularly in Figs. 1 and 4, to rest on the bottom plate A against the rear plate B and member D. The side plates M are provided with offsets N, to which are pivoted by means of a fulcrum pin O a link P. The pin O projects through a slot Q in the link P, and the other end of the link is pivoted at R to a bar S, with a handle T. The bar S is provided with a toe piece U, adapted to bear on the upper side of the link P, as shown more particularly in Fig. 4, while a spring V fits between the link P and bar S. W designates 75 studs or posts on the back plate B.

The operation of the invention is as follows: The member D is swung into position by means of the handle F and the link J engaged by the hook G. The side plates are 80 then forced against the sides of the member D, leaving between the side plates, member D, rear plate B and base A a cavity for the casting to be formed of molten metal poured into this hollow space, through a channel Y, 85 in one or both of the side plates M. The side plates are held in position by the spring V, forcing the link P and bar S apart, so that the bar S will abut against the stud W, as shown more particularly in Figs. 1 and 4. 90 When, however, the metal in the mold expands, the member D will be moved slightly outward against the tension of the spring L, which permits the hook G to be slightly turned while still engaged in the link J. The 95 side plates M will be moved slightly outward upon the expansion of the metal in the mold, as the springs V will be contracted and allow the links P to turn somewhat on their pivots, and the lower end of the link and the bar S 100 be brought closer together.

When it is desired to remove the side plate of the mold, the bar S is turned on its pivot R by means of the handle T, so as to swing the bar away from engagement with the 105 stud W, whereupon the plate M may be withdrawn by the handle T. The hook G may be then disengaged from the link J, by means of the handle I, by compressing the spring L, and the member D swung on its pivot by 110 the handle F.

In the modified form shown in Fig. 5 a

screw Z is inserted through a portion of the bar S and engages one end of the spring V, so that by means of the screw the tension of the spring V may be adjusted.

- 5 Having now described my invention (which may vary in its details without departing from the spirit thereof) what I claim and desire to secure by Letters Patent, is:—
1. A metal mold for casting articles, having a base; removable mold sections adapted to rest thereon; mechanism for locking said mold sections in place on said base; and yielding means for permitting a slight movement of the mold sections in different directions at various angles while in their locked positions, substantially as described.
  2. In a metal mold for casting articles, the combination with a base; of a mold section pivotally connected with said base; mechanism for locking the free end of said section on said base; and yielding means for permitting a slight movement of the mold section while in its locked position, substantially as described.
  - 25 3. In a metal mold for casting articles, the combination with a base; of a mold section; a lever pivoted to said section; and a device

on said base adapted to be yieldingly engaged by said lever to hold said mold in its locked position, substantially as described.

4. In a metal mold for casting articles, the combination with a base; of a mold section pivoted to swing to and from its operative position; a lever pivoted thereon; and a device on said base adapted to be yieldingly engaged by said lever, substantially as described.

5. In a metal mold for casting articles, the combination with a base; of a mold section rigidly secured thereto; a further section pivoted thereto; movable sections; mechanism for locking said movable sections to said rigid section and said pivoted section to said base; and yielding means for permitting said movable and pivoted sections a slight movement when in their locked positions, substantially as described.

In witness whereof I have hereunto set my hand on the 17th day of May, 1906.

JOHN H. SHAW.
